WIRE RECEPTACLE

George B. Hume, Kansas City, Mo., assignor to
Hume Manufacturing Company, North Kansas
City, Mo., a corporation of Missouri

Application August 21, 1950, Serial No. 11,866

Term of patent 14 years

(Cl. D58—2)

To all whom it may concern:

Be it known that I, George B. Hume, a citizen of the United States, residing at Kansas City, in the county of Jackson and State of Missouri, have invented a new, original, and ornamental Design for a Wire Receptacle, of which the following is a specification, reference being had to the accompanying drawing, forming a part thereof.

Fig. 1 is a top plan view of a wire receptacle, showing my new design.

Fig. 2 is a side elevational view thereof; and,

Fig. 3 is a top plan view of the wire receptacle, with the cover portion thereof in an open position.

I claim:

The ornamental design for a wire receptacle, as shown.

GEORGE B. HUME.
